UNITED STATES PATENT OFFICE.

WILLIAM H. MINER, OF CHICAGO, ILLINOIS.

DRAFT-RIGGING FOR RAILWAY-CARS.

1,139,791.

Specification of Letters Patent. Patented May 18, 1915.

Application filed July 22, 1912, Serial No. 710,839. Renewed April 5, 1915. Serial No. 19,333.

To all whom it may concern:

Be it known that I, WILLIAM H. MINER, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide a 15 friction draft rigging of high cushioning capacity.

In the drawings Figure 1 is a plan view partly in horizontal section of a railway draft rigging embodying my invention. 20 Fig. 2 is an elevation partly in vertical longitudinal section. Figs. 3 to 9 inclusive are enlarged details; Fig. 3 being an elevation partly in longitudinal section of the friction shell and contained parts shown in the state 25 of compression; Fig. 4 a front end view of the compression resisting member; Fig. 5 a perspective view of one of the shoes; Fig. 6 a perspective view of the wedge; Fig. 7 a perspective view of one of the friction rollers; and Figs. 8 and 9 perspective views of 30 the disks.

In the drawings 10, 10 represent a draft sill or parts of the car frame to which the draft rigging is attached, 11, 11 the stop 35 members, 12 the draw bar carry iron, 14 the end sill, 15 the buffer block, 16 the draw bar, 17 the draft yoke, 18 the front follower, 19 the tie plate and draft yoke carry plate; all of said parts being of well known construction, and serving their usual functions.

20 is the compression resisting member consisting of the friction shell 21 and the parts contained therein, hereinafter more 40 specifically enumerated. The friction shell 45 is open at its front end 22 and closed at its rear end 23 by the member 24, which is preferably integral with the friction shell 21, and performs the function of a rear follower. The shell is externally provided 50 at its rear end with the recess 25, the walls forming said recess providing inside the shell the boss 26 around which the outer spring 27 is seated against the rear inner face 28 of the friction shell, the boss being 55 provided at its inner end with the seat 29 for the inner spring 30. The friction shell

is provided with the internal friction face 31 with which the annular segmental friction shoes 32 are in frictional engagement.

The shoes 32 are preferably three in number, and each is provided with the internal friction face 33. The wedge 34 is pyramidal in shape, and is provided with the wedged faces 35, 35, said faces being equal in number to the friction shoes and with 60 the transverse shoulders 36, 36. Between each of the wedge faces 35 and the friction face 33 of the adjacent shoe is placed an anti-friction roller 37. Seated against the rear ends 38 of the friction shoes are the 65 resilient disks 39, 39, preferably concave disks with the concave surfaces of the forward pair facing the friction shoe, and the concave surfaces of the rear pair facing the springs 27 and 30, the forward end of 70 the said springs being seated against the 75 resilient disks.

The forward portion of the friction shell 21 is of larger diameter than the rearward portion thereof, so constructed as to form 80 the circular shoulder 40 against which the rear disk is seated upon the full compression of the springs 30 and 27. The member 24 at the rear end of the shell 21 is hollow 85 about the boss 26, thus permitting the spring 27 to be of exceptional length.

The wedge 34 is provided with the recess 41 to receive the head 42 of the connecting rod 43, which passes through the opening 44 in the wedge, rearwardly through the 90 openings 45 in the center of the disks 39, 39, and the opening 46 in the rear central portion of the shell into the recess 25, which is of suitable dimensions to receive the nut 47. In normal position the parts within the friction shell are in the relative positions illustrated in Figs. 1 and 2 of the drawings. The disks 39, 39 are of suitable strength so that upon the compression of the gear the said disks and the springs 30 and 27 are 95 fully compressed, and the rear disk is in engagement with the shoulder 40 of the shell before the said disks are in a position of full compression, as illustrated in Fig. 3. Thus when the forward movement of the 100 draw bar draws the compression resisting member 20 against the front follower 18, or when the rear movement of the draw bar thrusts the front follower 18 against the compression resisting member 20 toward the 105 end of the movement in addition to the resistance of the springs 27 and 30, and of the 110

resistance afforded by the frictional engagement of the friction shoes with the internal friction face of the shell there is added the resistance of the disks 39, which are compressed between the shoulder 40 and the rear ends 38 of the friction shoes, affording a high compression resisting capacity to the draft gear.

I claim:—

- 10 1. In a railway draft rigging, a compression resisting member comprising a friction shell, a wedge, friction shoes, springs and resilient disks within the shell, the shell being provided with an internal shoulder between which and the rear end of the friction shoes the resilient disks are compressed upon the full compression of the spring.
- 15 2. In a railway draft rigging, a compression resisting device comprising a friction shell provided with an internal annular shoulder in front of which the shell is of a larger internal diameter than back of the said shoulder, and a wedge, friction shoes, springs and resilient disks within the friction shell, the springs being seated at their rear end against the internal rear face of the friction shell, and at their forward end against the said disks, the disks being between the rear end of the friction shoes and the said springs, and being capable of full compression only when engaged between the said shoulder and the friction shoes.
- 20 3. In a railway draft rigging, a compres-

sion resisting member comprising a shell, friction mechanism, friction shoes and springs within the shell, a resilient member interposed between said springs and friction mechanism, said shell being provided with a seat between which and the friction shoes the said resilient member is engaged and adapted to be compressed.

4. In a railway draft rigging, a compression resisting member comprising a shell, friction mechanism and springs within the shell, a resilient member interposed between said springs and the friction mechanism, said shell having an internal seat against which the said resilient member is compressed by the friction mechanism after compressing movement of the springs.

5. In a draft gear, a shell having an internal shoulder in front of which the shell is of larger internal width than back of said shoulder, a wedge, friction shoes and a resilient member within the shell and springs, the said resilient member being seated between the friction shoes and said springs, the said resilient member being adapted to move with the friction shoes, and to be compressed thereby upon engaging said shoulder.

WILLIAM H. MINER.
